UNITED STATES PATENT OFFICE.

ANTON F. ERICKSON, OF PHILLIPSBURG, PENNSYLVANIA.

ATTACHMENT FOR AEROPLANES.

1,423,789.

Specification of Letters Patent. Patented July 25, 1922.

Application filed October 25, 1920. Serial No. 419,335.

To all whom it may concern:

Be it known that I, ANTON F. ERICKSON, a citizen of the United States, residing at Phillipsburg, in the county of Center and 5 State of Pennsylvania, have invented a new and useful Attachment for Aeroplanes, of which the following is a specification.

This invention aims to provide novel means whereby an aeroplane may be prevented from dropping abruptly.

One of the objects of the invention is to provide novel means for operating a curtain which may be extended at any time, to retard the falling of an aeroplane.

15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, 25 within the scope of what is claimed, changes in the precise embodiment of the invention shown can be made without departing from the spirit of the invention.

In the accompanying drawings:

30 Figure 1 shows in top plan, a device constructed in accordance with the invention; Figure 2 is a longitudinal section wherein parts appear in elevation; Figure 3 is a fragmental vertical section taken through the 35 forward portion of the aeroplane; Figure 4 is a fragmental longitudinal section taken through the body of the aeroplane; Figure 5 is a section on the line 5—5 of Figure 4; Figure 6 is a section on the line 6—6 of 40 Figure 4; Figure 7 is a section on the line 7—7 of Figure 4.

The numeral 1 denotes the body of an aeroplane, rear frame members 2 and 3 being provided and front frame members 4 and 5 being shown. As upper sustaining plane 6 is carried by the frame members 2 and 3, a lower sustaining plane 7 being carried by the said members. The front frame members 4 and 5 carry an upper sustaining 45 plane 8 and a lower sustaining plane 9. The horizontal rudders appear at 10, and the vertical rudder is indicated by the reference numeral 11. The propeller is shown at 12 and the engine is indicated at 14—the fore- 50 going being an aeroplane construction for which no novelty is claimed, saving in so far

as it may enter into patentable relation with parts hereinafter described.

Supports 15, which may be cables, extend between the frame members 3 and 4. A 60 housing 16 is superposed on the plane 8 and is open at one end. A flexible curtain 17 is provided, the same having a pocket 18. The curtain 17 and its pocket 18 may be reinforced by a netting 19, made of rope or any 65 other suitable material. The forward end of the curtain 17 is carried by a rod 20 located in the housing 16 and connected to the plane 8 as indicated at 21. The rear end of the curtain 17 is connected to a rod 22. 70 The curtain 17 may be rolled around the rod 22 and may be disposed within the housing 16, as shown in Figure 3, the curtain being held in the housing by spring retainers 23 secured to the plane 8 and adapted to 75 bear yieldingly upon the rolled up curtain. Flexible elements 24 are connected to the rod 22 and are rolled up with the curtain 17. The flexible elements 24 extend rearwardly, around fairleads 25 on the plane 6, and are 80 extended downwardly, and are connected to a rotatable member 26, preferably in the form of a drum, mounted to rotate on a shaft 27 journaled in bearings 28 and 29 mounted on the body 1.

One end of a torsion spring 79 is secured to the drum 26, the other end of the spring being secured to the shaft 27. The spring 79 may be located within the drum 26 if desired. On one end of the drum 26 there is a 90 ratchet wheel 30 adapted to cooperate with a pawl 31 pivotally supported on the bearing member 28. In one end of the drum 26 there is a seat 32 adapted to be engaged by a latch 33 mounted to reciprocate in a casing 34 on the bearing 29, the casing having a slot 35 receiving a finger 36 on the latch 33. The finger 36 lies in the path of a cam 37 on a shaft 38, the shaft being journaled in the bearing 29 and in a bearing 39 on the 100 body 1, the shaft having a crank 40 located within convenient reach of the operator. A worm wheel 41 is secured to the shaft 27 and cooperates with a worm 42 on a shaft 43 provided with a crank 44, the shaft 43 being journaled in brackets 45 on the bearing 29. The construction of the worm 42 and the worm wheel 41 is such that, although rotation may be imparted to the worm wheel 41 from the worm 42, the worm wheel 41 110 cannot react on the worm 42 and rotate the shaft 43.

In practical operation, the pawl 31 cooperating with the ratchet wheel 30 holds the drum 26 against rotation, the shaft 27 being rotated by means of the worm wheel 41, 5 the worm 42 and the shaft 43, to put the spring 79 under tension. Supposing that the curtain 17 is rolled up and located within the housing 16, as shown in Figure 3, the operator may actuate the shaft 38 by means 10 of the crank 40, the cam 37 engaging the finger 36 and retracting the latch 33 out of engagement with the seat 32 in the end of the drum 26. Thereupon the drum 26 is rendered responsive to the action of the torsion spring 79. When the drum 26 is rotated by the spring 79 the pawl 31 clicks over the ratchet 30, the flexible elements 24 being wound on the drum 26. When the 15 flexible elements are wound on the drum, 20 the curtain 17 is unrolled and carried backwardly, along with the rod 22, the curtain traversing the supports 15 and the edge of the curtain, ultimately, arriving beneath the plane 6, as shown in Figure 2. The pocket 25 18 thereupon will open and it will be obvious that the curtain and its pocket serve as a means for supporting the aeroplane and for easing the plane downwardly toward the ground. The pawl 31 cooperating with the 30 ratchet wheel prevents the flexible elements 24 from unwinding due to air pressure against the curtain and its pocket when the aeroplane is descending.

The device will operate in a satisfactory 35 way, even though the aeroplane be turned upsidedown. Thus, when the aeroplane is inverted, the curtain 17 and its pocket 18 will be engaged by the supports 15 and will be held flat or nearly so. The weight of the 40 engine 14, under such circumstances, is above the curtain, and the aeroplane will again be inverted into the position shown in Figure 2 whereupon the curtain 17 and its pocket 18 will exercise their functions and 45 prevent an abrupt dropping of the plane to the ground.

The center of mass of the body of the machine is so located that the machine will

tend to right itself, when the machine is inverted, and when the curtain is extended, 50 the pocket being prevented by the support from opening.

Having thus described the invention, what is claimed is:—

1. In a device of the class described, an 55 aeroplane; a curtain connected at one end to the aeroplane, the other end of the curtain being formed into a roll; a flexible element connected to the last specified end of the curtain and rolled in with the curtain; a drum journaled on the aeroplane, the flexible element being connected to the drum; means for driving the drum; and mechanism under the control of an operator for rendering the drum responsive to said means, thereby 60 to effect an unrolling of the curtain.

2. An aeroplane comprising a body and spaced planes; a curtain extensible between the planes and including a pocket; and a support interposed between the body and 70 the curtain, the support being disposed between the curtain and the body thereby to prevent the pocket from opening when the aeroplane is inverted, the center of mass of the body being so located with respect to 75 the curtain that the body will serve as a counterpoise for restoring the plane to normal position, thereby to permit an opening of the pocket.

3. An aeroplane comprising a housing; a 80 curtain having one end secured within the housing, the other end of the curtain being fashioned into a roll within the housing; a retainer in the housing and engaging the roll releasably; and means under the control 85 of an operator for unrolling said end of the curtain and for withdrawing the curtain from the housing.

In testimony that I claim the foregoing as my own, I have hereto affixed my signature 90 in the presence of two witnesses.

ANTON F. ERICKSON.
